UNITED STATES PATENT OFFICE.

WILLIAM A. KALER, OF LARWILL, INDIANA.

STENO-TELEGRAPH INSTRUMENT.

SPECIFICATION forming part of Letters Patent No. 352,059, dated November 2, 1886.

Application filed October 10, 1885. Serial No. 179,639. (No model.)

To all whom it may concern:

Be it known that I, WILLIAM A. KALER, a citizen of the United States, and a resident of Larwill, in the county of Whitley and State of Indiana, have invented certain new and useful Improvements in Steno-Telegraphic Instruments; and I do hereby declare that the following is a full, clear, and exact description of the invention, which will enable others skilled in the art to which it appertains to make and use the same, reference being had to the accompanying drawings, which form a part of this specification, and in which—

Figure 1 is a diagram of the entire system of my improved steno-telegraphic apparatus, only one key and recording-lever being shown at each end of the line-wire. Fig. 2 is a plan view of one of the key-boards, showing the several wire-connections of the same. Fig. 3 is a similar view of one of the recording-instruments. Fig. 4 is a front view, on an enlarged scale, of the paper-carrying mechanism of the recording-instruments. Fig. 5 is a rear view of the same. Fig. 6 is a plan view of one of the recording-instruments with the paper-carrying mechanism removed. Fig. 7 is a side elevation of one of the keys of the key-boards, showing the same in its normal position, and Fig. 8 is a similar view of one of the recording-levers or type-bars.

The same letters of reference indicate corresponding parts in all the figures.

My invention has relation to printing telegraphs; and it consists in the improved construction, arrangement, and combination of parts, as will be hereinafter fully described, and pointed out in the claims.

Referring to the several parts by letter, A represents the key-boards, of wood or other non-conducting material, of which there is one at each end of the line-wire C. B B indicate the recording-instruments, of which there is also one at each end of the line C; and C indicates the main-line wire or wires, the apparatus using five wires, one for each of the recording-levers, which separately or in combination print the different characters of the alphabet, as hereinafter described.

D D indicate the batteries in the local circuits at each end of the line, and E E indicate the ground-places with which one wire of each battery communicates in the usual manner.

The keys of each key-board consist of a series of Morse keys arranged similar to the keys of the Bartholomew stenograph, there being on each key-board a central key, F, and four keys on each side of the said central key, each of the keys having upon its outer end a button, H, for the fingers. Each of these keys is centrally pivoted upon a short metallic fulcrum-post, M, the rear ends of the keys resting normally upon metallic posts I, while beneath their free ends, and in a position to be touched by the same when the keys are depressed by the fingers of the operator, are metallic buttons J. The pairs of posts I of each key-board corresponding to each other are connected together by means of wires K, passing out at one side to the local recording-instrument at that end of the line, and the posts J, corresponding to each other, are similarly connected to each other by wires L, passing out at one side of the key-board to the local battery D, while the fulcrum-posts M of the keys corresponding to each other are connected by wires N, which pass out at one side of the key-board and pass into the line-wires, each key at one side of the middle key having a key corresponding to it upon the other side of the said central key, with which it is coupled, as above described. The object of this arrangement is to enable the operator to use the fingers of both hands in telegraphing, as to touch any key to the side of the central key produces the same result as touching its coupled key on the other side of the central key, and by thus enabling the operator to use both hands a great degree of rapidity is attained, the hands working alternately, as it were, much more rapidly than one hand alone could work.

The recording-instruments, one of which, as previously stated, is located at each end of the line, are each provided with five electromagnets, O, and one end, O', of the wire of each of these magnets is connected with a wire, K, from one pair of posts I at the inner ends of the keys of the key-board, while the other end, P, of the wire of each magnet passes to the ground-wire Q of the battery, each electromagnet corresponding to and being operated by one pair of coupled keys upon the key-board, with the exception of one electromagnet, which is connected in a similar man-

ner to the central key, F. The armatures of each of these electro-magnets are secured upon the outer ends of levers or type-bars S, which levers are centrally pivoted and have 5 their inner ends arranged in a straight row, and provided each with a head, T, having a straight dash upon its face, the dashes upon the faces of the five heads forming a straight line transverse to the length of the paper ribbon which travels above them.

Y Z indicate two parallel frame-pieces which are secured upon the base of each recording-instrument, Y representing the front frame-piece and Z the rear frame-piece, and between 15 the upper ends of these frame-pieces is journaled a roller or cylinder, X, beneath which passes a paper ribbon, U, which is wound upon a roller or disk, V, journaled between two uprights, W W, rigidly secured at one side of 20 the frame-pieces Y Z. The cylinder X is provided at its forward end with a ratchet-wheel, A', and a pawl, R', pivoted upon the inner side of the front frame-piece, Y, engages with the 25 said ratchet-wheel and thereby prevents the cylinder X from turning in the wrong direction.

E' represents a vertical bar which slides in a vertical opening in the front frame-piece, Y, the said bar being provided with a spring- 30 catch, C', which engages with the ratchet-wheel A', and the bar E' is also formed at its lower end with a transverse bar, D', which is transverse to the inner ends of all the armature-levers S, extending above them forward of their 35 operative straight ends, so as not to prevent the said ends from coming in contact with the paper ribbon, as hereinafter described. The upper end of the vertical sliding bar E' is secured to the lower end of a spring, F', which is 40 coiled in a recess, G', on the front frame-piece, Y, and bears with its upper end against a plate, H', at the lower end of a set-screw, I', working in the upper portion of the front frame-piece, the said screw serving to adjust 45 the tension of the coiled spring F'.

To the rear end of the shaft of the cylinder X, beneath which the paper ribbon passes, and which may be denominated the "paper-carrying cylinder," is secured a cog-wheel, J', which 50 meshes with a cog-wheel, K, which is pivoted at the outer end of an arm, which is in turn pivoted at its inner end upon the rear end of the shaft of the paper-carrying cylinder, so that the said cog-wheel may be swung upon 55 the arm from one side of the paper-carrying cylinder to the other and still continue to mesh with the cog-wheel upon the rear end of the cylinder-shaft.

O' indicates the inking-ribbon, which is 60 wound at each end around a roller, N', the said ribbon-carrying rollers being journaled between the front and rear side pieces of the frame in such positions as to carry the inking-ribbon immediately beneath the paper-carrying cylinder X. The rear end of one of 65 these rollers is provided with a pinion, M',

with which the cog-wheel K' meshes when the pivoted arm L' is swung to that side, while when the arm L' is swung to the opposite side the wheel K' meshes with the small pinion P', 70 interposed between it and the pinion M' on the other roller, by which arrangement the second roller is caused to revolve in a direction opposite to that in which the first roller revolves, so as to carry the ribbon back when it 75 has been all wound upon the said first roller.

An arm, Q', is pivoted at one end between the uprights W W, and has a short arm projecting to the outer side of the uprights, through a perforation in which arm passes a set-screw, 80 R', having attached to its lower end a spring, S, the other or lower end of the said spring being secured to the base of the instrument, and the inner end of the arm Q' is provided with a guide-bail, T', through which the paper ribbon passes, while the innermost end of the arm has a roller, U', journaled in it, which bears against the under side of the paper ribbon, pressing it against the paper-carrying cylinder, and by means of the set-screw R' the 85 spring-tension with which the roller U' presses against the paper may be readily adjusted. A second roller, U', is journaled in the side pieces of the main frame, so as to press against the paper ribbon on the opposite side of the 90 cylinder X, as shown, thereby holding the paper ribbon up firmly against the said cylinder.

The operation of my improved apparatus is as follows: The rear ends of the keys on each 100 key-board rest normally in contact with the rear posts, I, thereby communicating, through their wire-connections K, with the electro-magnets of the recording-instruments, the armature-levers S resting normally with their 105 rear ends lowered, and their free ends, which carry the armatures, elevated above and out of contact with their electro-magnets. When the operator at one end of the line—say, for example, at the station marked A⁵ on the 110 diagram, Fig. 1 of the drawings—wishes to send a message to the station at the other end of the line, he depresses one or more keys, according to the number and position of the 115 dashes required to indicate the desired letter, (I prefer to use the alphabet used with Bartholomew's stenograph,) and when the forward end of the key or keys is depressed to touch the buttons J beneath them the current from the battery D will pass through the wire 120 L, button J, the depressed key, the fulcrum M of the same, the wire N, through the main-line wire C, through the fulcrum-post of the corresponding key, the key, and the rear post, I, of the key-board at the other end, A⁶, of the 125 line, and through the wire K of the said rear post to the corresponding electro-magnet, which is thereby electrified or actuated, and by attracting or drawing down the armature 130 of its type-bar S will elevate the rear end of the said type-lever, which will strike against the inking-ribbon and make an im-

pression on the paper ribbon in the manner usual with type-writers and stenographs, as will be readily understood.

It will be seen from the foregoing that by depressing one or more keys at one end of the line the desired dash, or combination of dashes indicating the required letter, will be printed at the other end of the line, and the message will stand recorded upon the paper ribbon, so that it will not be absolutely necessary for the operator to be present at the moment of receipt. When the rear end of the type-lever strikes upward to print the dash, it elevates the spring-cushioned transverse bar D', against which it strikes, and on the descent of the type-lever the bar E' will be forced down by its spring, and in its descent the spring-pawl C', attached to it, will engage the ratchet-wheel A' upon the paper-ribbon cylinder, thereby moving the same and the paper ribbon with it one space ahead. As the paper-carrying cylinder revolves it will revolve one of the rollers carrying the inking-ribbon, causing the said ribbon to wind upon the said roller, and after the said ribbon has been completely wound upon one roller the swinging arm L' may be swung over to the other side, causing the cog-wheel K' to engage with the pinion upon the end of the other roller, or the small intervening pinion, P', as the case may be, thereby causing the inking-ribbon to be wound in the opposite direction.

It will be seen from the foregoing that when the keys at one end of the line are depressed the current from the battery at that end will pass through the depressed keys, their fulcrums, and the main-line wires to the fulcrums of the keys at the distant station through the said keys, which are in contact with their rear posts, I, to the electro-magnets, thereby attracting the armatures of the corresponding type-levers, the rear ends of which are thus elevated to print the desired dash or dashes, the upward stroke of the lever or levers raising the transverse bar D', which in falling moves the recording-paper and inking-ribbon forward one space, as above described.

Each recorder is represented as having an individual line-wire, but my apparatus may be used in connection with any well-known multiplex system of transmission.

Having thus described my invention, I claim and desire to secure by Letters Patent of the United States—

1. In a steno-telegraph apparatus, a key-board having one central key and a number of keys arranged at both sides of the central key, all the posts of the keys at one side of the central key being connected by wires to the posts of the corresponding keys upon the other side of the central key, as and for the purpose shown and set forth.

2. In a steno-telegraph apparatus, in combination with a number of type-bars, a paper-carrying device consisting of a paper-carry-

ing roller having a ratchet-wheel at one end, a spring-pawl engaging the ratchet-wheel, a spring-cushioned vertically-sliding bar having a transverse bar at its lower end above the inner ends of the type-bars, and a spring-pawl attached to the transverse bar and engaging the ratchet-wheel upon the paper-carrying cylinder, as and for the purpose shown and set forth.

75

3. In a steno-telegraph apparatus, the combination of a number of type-bars with a paper-carrying device, and an inking-ribbon-carrying device consisting of a paper-carrying cylinder having a cog-wheel at its rear end, an arm pivoted to swing upon the shaft of the paper-carrying cylinder, a cog-wheel journaled at the outer end of the arm and meshing with the cog-wheel upon the paper-carrying cylinder, rollers having the ends of the ribbon wound upon them and provided with pinions at their ends, and alternately meshing with the cog-wheel upon the swinging arm, and a pinion interposed between the cog-wheel upon the swinging arm and one of the pinions upon the inking-ribbon-carrying rollers, as and for the purpose shown and set forth.

4. In a steno-telegraph apparatus, the combination of a number of type-bars with a paper-carrying cylinder, two uprights having a roll of paper journaled between them, a spring-arm pivoted between the two uprights and having an outwardly-projecting perforated arm and an inwardly-projecting spring-arm provided with a guide-bail for the paper strip, and with a roller at its outer end for forcing the paper strip against the paper-carrying roller, a set-screw passing through the perforated short arm of the spring-lever, and a spiral spring secured to the base of the device and to the lower end of the set-screw, as and for the purpose shown and set forth.

5. In a steno-telegraph apparatus, the combination of batteries at the ends of the line, key-boards at the ends of the line having the keys arranged similar to the stenograph-keys, and having the outer posts for the keys connected to the batteries, wires connected to the fulcrum-posts of the keys at both ends, and recording-instruments at the ends of the line, consisting of a number of magnets corresponding to the keys and having each one wire connected to the inner post of its corresponding key upon the key-board, and having each one wire connected to the battery ground-wire, a number of type-levers having type-heads at their inner ends and armatures at their outer ends supported above the magnets, and a paper and inking-ribbon carrying device, as and for the purpose shown and set forth.

In testimony that I claim the foregoing as my own I have hereunto affixed my signature in presence of two witnesses.

WILLIAM A. KALER.
